UNITED STATES PATENT OFFICE.

WATT C. DAUGHERTY, OF MONONGAHELA, PENNSYLVANIA, ASSIGNOR OF ONE-HALF
TO PHILIP GINSBERG, OF MONONGAHELA, PENNSYLVANIA.

CHARGING DEVICE.

1,239,571.

Specification of Letters Patent. Patented Sept. 11, 1917.

Application filed July 5, 1916. Serial No. 107,683.

To all whom it may concern:

Be it known that I, WATT C. DAUGHERTY, a citizen of the United States, residing at Monongahela, in the county of Washington and State of Pennsylvania, have invented 5 certain new and useful Improvements in Charging Devices, of which the following is a specification, reference being had to the accompanying drawings.

10 This invention relates to certain improvements in charging devices for zinc furnaces or the like, and it is an object of the invention to provide a charger of this character having novel and improved means whereby 15 the delivery tube is capable of vertical adjustment in order to permit the same to be employed in connection with retorts at varying heights.

It is also an object of the invention to 20 provide a novel and improved device of this general character wherein the charge is conveniently deposited within the delivery tube and wherein a reciprocating member is employed for forcing the charge from 25 within the tube.

It is also an object of the invention to 30 provide novel and improved means including a reciprocating member which is capable of vertical adjustment and which serves as a scraper adapted to extend within a retort together with means coacting with the reciprocating member for delivering a blast of air within a retort.

The invention consists in the details of 35 construction and in the combination and arrangement of the several parts of my improved charging device whereby certain important advantages are attained and the device is rendered simpler, less expensive 40 and otherwise more convenient and advantageous for use, all as will be hereinafter more fully set forth.

The novel features of the invention will 45 hereinafter be definitely claimed.

50 In order that my invention may be the better understood, I will now proceed to describe the same with reference to the accompanying drawings, wherein—

Figure 1 is an elevational view of a 55 charger constructed in accordance with an embodiment of my invention with portions broken away;

Fig. 2 is a view in top plan of the device as disclosed in Fig. 1;

Fig. 3 is a sectional view taken substantially on the line 3—3 of Fig. 1;

Fig. 4 is a sectional view taken substantially on the line 4—4 of Fig. 1; and

Fig. 5 is an enlarged sectional view taken substantially on the line 5—5 of Fig. 2.

As disclosed in the accompanying drawings, 1 denotes a suitable frame provided with the supporting wheels 2 adapted to travel upon the trackway 3, the end wheels 2 being adapted to be positively driven.

As herein set forth, each pair of end wheels 2 is affixed to the axle 4. Each of the axles 4 is provided with the gear 5 in mesh with the gear 6 loosely mounted upon the shaft 7 and which coacts with the clutch member 8 in a conventional manner whereby it will be perceived that the shaft 7 may be operatively engaged with the axle 4 when the necessities of practice may so require.

The shaft 7 is operatively engaged, as indicated at 9, with the motor M carried by the platform P secured to the frame 1. Each of the motors M is capable of operation independently of the other and preferably in accordance with which of the two 80 mechanisms carried by the frame is in use as will hereinafter be more particularly understood.

Extending upwardly from the frame 1 at a predetermined point intermediate its 85 length are the transversely aligned pairs of tubular uprights 10, the longitudinally aligned uprights having their opposed faces provided with the longitudinally directed slots 11 through which are directed the extremities of the beams 12, the portions of the beams 12 within the uprights 10 having threaded therethrough the shafts 14 positioned within the uprights 10 and mounted for rotary movement but incapable of 90 lengthwise movement.

The lower end of each of the shafts 14 is provided with a worm gear 15 in mesh with the worm 16 carried by a longitudinally disposed shaft 17. The forward end of the 100 shaft 17 is provided with a bevel gear 18 in mesh with a gear 19 which also has affixed thereto the straight gear 20 in mesh with a gear 21 affixed to the transverse shaft

22, the inner end of which being provided with the gear 23 in mesh with the gear 24 loosely mounted on the shaft 7 and with which coacts a conventional clutch 25 for causing said gear 24 to rotate in unison with the shaft 7 when it is desired to raise or lower the beams 12.

The beams 12 support the table 26 which in turn serves as a support for the delivery tube T extending laterally relative to the frame 1 and of predetermined length and has telescopically engaged with its outer end portion the extension section 27 whereby the same may be readily adjusted in accordance 15 with the furnace with which the same is adapted to be applied. As herein disclosed, the requisite endwise movement is given to the extension 27 through the medium of the operating rod 28 as is particularly illustrated in Fig. 3.

In communication with the delivery tube T through the top thereof are the feeding tubes 29 having their discharge ends in predetermined spaced relation longitudinally 25 of the tube T, while their upper extremities are in communication with the chute 30 disposed on a predetermined upward incline and leading from the hopper 31 in which the material is initially deposited.

30 Traveling within the chute 30 and leading from the hopper 31 is the endless conveyer 32 herein disclosed as operatively connected, as at 33, with the motor M' underslung relative to the table 26 and adapted to be operatively connected with a suitable source of electrical energy and controlled in any desired manner. The conveyer 32 serves to conduct the material from the hopper 31 to the feeding tubes 29 and in order to control 35 the passage of the material through said tubes, I find it of advantage to employ the slide valve 34 adapted to intersect said tubes adjacent their upper ends and which is adapted to be employed more particularly in connection with the innermost tube 29.

50 Mounted for reciprocatory movement within the tube T is the plunger head 35 suitably secured to the forward end of the plunger rod 36 herein disclosed as provided along its under face with the rack 37 adapted to mesh with the pinion 38 operatively engaged, as at 39, with the motor M² whereby it will be perceived that upon requisite operation of the motor M² the head 35 may 55 be forced outwardly to discharge the contents within the tube T or retracted when it is desired to deliver a new charge within the tube T through the feeding tubes 29. The motor M² is also adapted to be operatively 60 connected with a suitable source of electrical energy and to be controlled in any desired manner. It is to be understood that as said electrical connections embodied in the invention as herein disclosed in the details form no

part of my invention, it is thought that a 65 detail description and illustration thereof is unnecessary.

It is thought to be self-evident that upon requisite operation of the shafts 17, the table 26 may be raised or lowered in accordance 70 with the height of the retort adapted to be charged.

The frame 1 has also extending upwardly therefrom the pairs of tubular uprights 40 similar to the uprights 10 hereinbefore referred to and with which is operatively engaged the vertically adjustable table 41, the adjustment of which being substantially the same as has been set forth relative to the table 26.

80 The table 26 has mounted thereupon for endwise movement, the elongated tubular scraping member 42 which is adapted to be forced within a retort and for which reason the outer end thereof is provided with the 85 scraping blades 43. The outer end of the member 42 is provided with a perforate head 44 through which a blast of air or the like is adapted to be emitted to further facilitate the cleansing of a retort, and as is particularly illustrated in Fig. 4, the head 44 has in communication therewith the tubing 45 leading from the fan 46 or other source of air under pressure. As herein disclosed, the fan 46 is adapted to be operated by the motor 90 M³ operatively connected with a suitable 95 source of electrical energy.

100 The member 42 has its under face provided with the rack 47 in mesh with the gear 48 rotatably supported by the table 41 and which is operatively engaged, as at 49, with the motor M⁴ also suitably connected with a desired source of electrical energy. By the requisite operation of the motor M⁴ it will be perceived that the member 42 may be extended or retracted as desired.

110 From the foregoing description, it is thought to be obvious that a charging device constructed in accordance with my invention is of an extremely simple and comparatively inexpensive nature and is particularly well adapted for use by reason of the convenience and facility with which it may be assembled, and it will also be obvious that 115 my invention is susceptible of some change and modification without material departure from the principles and spirit thereof and for this reason I do not wish to be understood as limiting myself to the precise arrangement and formation of the several 120 parts herein shown in carrying out my invention in practice, except as hereinafter claimed.

I claim:

125 A device of the character described including a vertically adjustable table, a reciprocating member mounted upon the table and provided with a rack, a gear wheel rotatably

supported by the under surface of the table, said table being provided with an opening through which said gear extends to mesh with the rack, and a driven member depending from the table and operatively engaged with the gear for rotating the same.

In testimony whereof I hereunto affix my signature in the presence of two witnesses.

WATT C. DAUGHERTY.

Witnesses:

HARRY W. CANNON,
B. S. ALLEN.
